UNITED STATES PATENT OFFICE.

HARRY G. PEAKE, OF SAN FRANCISCO, CALIFORNIA.

CASING-JACK.

1,170,843.

Specification of Letters Patent.

Patented Feb. 8, 1916.

Application filed June 7, 1915. Serial No. 32,611.

To all whom it may concern:

Be it known that I, HARRY G. PEAKE, a citizen of the United States, residing in the city and county of San Francisco and State of California, have invented new and useful Improvements in Casing-Jacks, of which the following is a specification.

This invention relates to a casing jack.

One of the objects of the present invention is to provide a simple, substantial, compact, easily operated jack of the character described which has a stationary and a movable clutch or gripping member adapted to embrace the pipe or casing to be removed.

Another object of the invention is to provide a toggle lever mechanism, whereby the movable gripping member is operated, and to provide means for automatically and successively engaging and releasing the gripping members while the pipe or casing is being lifted.

Further objects will hereinafter more fully appear.

The invention consists of the parts and the construction and combination of parts as hereinafter more fully described and claimed, having reference to the accompanying drawings, in which—

Figure 1 is a side elevation of the casing jack. Fig. 2 is a cross section on line 2—2 of Fig. 1.

The jack proper consists of a stationary base member A in which is formed a central opening 2. Pivotaly mounted, as at 3, is one member 4 of a toggle link, and formed integrally with said member is a lever 5. Pivotaly attached, as at 6, to the link member 4 is a second link 7, the upper end of which is pivotally attached to a movable collar 8 in which is formed a central opening 9. Two or more levers 5, with connected toggle links 4 and 7, may be interposed between the stationary base section A and the movable collar 8 and these levers may be operated by any suitable means, or, as here shown, by a bridle connection 9 which may be raised or lowered by the cable 10 and any suitable mechanism not here shown.

Loosely mounted in guide slots, formed around the central opening 2 in the lower base section, is a plurality of wedge-shaped gripping members 12, and similarly mounted in the upper collar 8 is a plurality of wedge-shaped gripping members 13.

In operation, when it is desired to remove a pipe or casing, such as indicated at 14,

from a well, it is only necessary to slip the jack over the upper end of the casing, as indicated in Fig. 1, and support same on a pair of timbers as shown in Fig. 1 or like means. The levers 5 are then raised and lowered by means of the bridle 9 and cable 10 and an upward movement of the levers will force the toggle links inwardly against the casing 14, causing the collar 8 to be moved in an upward direction. The wedges 13 will in this manner grip the pipe and cause the latter to be raised in unison with the collar 8; the lower wedges 12 being inactive during the upward movement of the collar 8. The moment the levers 5 are lowered the collar 8 will also be lowered, together with the gripping wedges 13. The lower wedges 12 will then be forced into engagement with the casing, if this has a tendency to settle, and thus grip and lock it from dropping or settling down.

A jack constructed as here shown has the advantage of pulling the casing from the ground more rapidly than the ordinary method. It, furthermore, prevents any injury to the threads and couplings on the casing. The usual method of pulling a casing is with the pulling jar, which is virtually a hammer striking an upward blow on the inside of a cap which is screwed on the top length of a casing. This constant hammering has a tendency to crystallize the metal in the pipe, and it is not an uncommon occurrence to have the thread portion break off. The device here shown entirely eliminates this feature as the pull is constant. The jack also eliminates any possibility of the pipe slipping back into the hole, as the wedges in the lower member A prevent this; consequently any gain made in pulling the pipe is retained. This is of great assistance when the pipe has been driven through clay. This material being more or less springy, the pipe may easily be brought up, say, one-quarter of an inch by a blow from the pulling jar, but before another blow is struck, it settles back into its original position.

The jack is simple and substantial in construction and easy to operate and can be readily moved about from place to place when needed.

The materials and finish of the several parts of the apparatus are such as the experience and judgment of the manufacturer may dictate.

I wish it understood that various changes

in form, proportions and details of construction may be restored to within the scope of the appended claims, and that I do not wish to limit myself to the specific design and construction here shown.

Having thus described my invention, what I claim and desire to secure by Letters Patent is—

1. In a jack, a base and a top member spaced above the base and each apertured to receive a pipe, a pair of toggle links comprising short parts pivoted to the base at their lower ends and angular lever extending out from said short parts, and vertical links pivoted at the lower ends to the upper ends of the short parts and to the top member and normally diverging at their lower ends whereby upon upward movement of the levers the vertical links will be moved in-

wardly at their lower ends to thus move the top member upwardly.

2. In a pipe jack, an upper movable member and a lower stationary member, a pair of means to raise the upper member located on opposite sides of the members and connected thereto, actuating means for each of the raising means operable by upward movement thereof, and means connected to said actuating means to move same upwardly in unison while the lower member remains stationary.

In testimony whereof I have hereunto set my hand in the presence of two subscribing witnesses.

HARRY G. PEAKE.
